UNITED STATES PATENT OFFICE

2,290,158

AUTOMATIC BAG PACKAGE MAKING AND
FILLING MACHINEMervin Allatt, Plainfield, N. J., assignor to Millie
Patent Holding Co., Inc., New York, N. Y., a
corporation of New York

Application August 21, 1935, Serial No. 37,257

13 Claims. (Cl. 226—53)

This invention relates to packaging machinery of the bag making and filling type. More particularly the invention is directed to full automatic machines for making complete articles, such as tea-balls or other essence containing products, in quantity production and for delivering each article with a string handle and tag attached thereto in a desirable non-tangling position ready for packing in shipping containers.

Among the objects of the invention is to provide an improved machine for making articles of the character described comprising relatively few and simple parts which form a combination of compactly arranged cooperating apparatus, devices and mechanisms for automatically performing all the various operations necessary to completely manufacture said articles with string handles and tags and to deliver same continuously ready for packing in shipping containers, which shall require minimum attention in operation, which shall be relatively inexpensive to construct yet have a large output capacity, and which shall be practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawings, in which is shown various possible illustrative embodiments of this invention,

Figure 1 is a front elevational view of a tea-ball making machine embodying the invention.

Figure 2 is a plan view of the bag taken on line 2—2 in Figure 1.

Figure 3 is a detailed view corresponding to a section taken on line 3—3 in Figure 1 showing the clutch mechanism in effective position.

Figure 4 is a view similar to Figure 3 showing the clutch mechanism in the ineffective position.

Figure 5 is a sectional view taken through the machine at line 5—5 in Figure 2.

Figure 6 is a cross-sectional view taken above the main crank shaft at line 6—6 in Figure 5.

Figure 7 is a detailed front view of the main clutch control.

Figure 8 is a cross-sectional view taken on line 8—8 in Figure 7.

Figure 9 is an end elevational view of a portion of the machine showing the tag feeding and attaching mechanism with the stapling means omitted.

Figures 10 and 11 are cross sectional views taken on lines 10—10 and 11—11, respectively, in Figure 9.

Figure 12 is a cross-sectional view showing the bag material severing and sewing means.

Figure 13 is a detailed cross-sectional view taken on line 13—13 in Figure 12 showing the thread cutting and separating means.

Figure 14 is a detailed front view showing the machine needle, presser foot and material guiding means for sewing the bottom closure seam.

Figure 14a is a detailed elevational view showing the sewing machine feed dog and guide for sewing the bottom closure seam.

Figure 15 is a detailed cross-sectional view taken on line 15—15 of Figure 14.

Figure 16 is a detailed front view in elevation of the bag material feeding member corresponding to a view taken on line 16—16 in Figure 12.

Figure 17 is a cross-sectional view taken on line 17—17 in Figure 16.

Figure 18 is a cross-sectional view taken on line 18—18 in Figure 16 showing a one way clutching means.

Figure 19 is a detailed front view of the bag tea filling means.

Figure 20 is a cross-sectional view taken on line 20—20 in Figure 19.

Figure 21 is a fragmentary detailed section in plan taken on line 21—21 in Figure 19.

Figure 22 is a detailed front elevational view of the transfer means from the bag filling to the top closure means.

Figure 23 is a cross-sectional view taken on line 23—23 in Figure 22.

Figure 24 is a detailed view taken in plan on line 24—24 in Figure 23.

Figure 25 is a detailed plan view of the carrier for the top closure means.

Figure 26 is a detailed cross sectional view in elevation taken on line 26—26 in Figure 25.

Figure 27 is a detailed front view taken on line 27—27 in Figure 26 showing the machine needle, presser foot and material guiding means for the top closure.

Figure 28 is a detailed plan view of the thread severing means for separating the bags.

Figure 29 is a cross-sectional view taken on line 29—29 in Figure 28.

Figure 30 is a sectional view taken on line 30—30 in Figure 29.

Figure 31 is a detailed view similar to Figure 29 showing the shears open.

Figure 32 is a detailed sectional view corre-

sponding to a section taken on line 32—32 in Figure 30.

Figure 33 is a detailed plan view of the tag feeding, attaching and discharging means.

Figure 34 is a detailed cross-sectional view taken on line 34—34 in Figure 33.

Figures 35, 36 and 37 are detailed cross-sectional views taken on lines 35—35, 36—36 and 37—37, respectively, in Figure 34.

Figure 38 is a detailed cross sectional view of the staple wire feeding means taken on line 38—38 in Figure 35.

Figure 38a is a cross-sectional view of the staple wire before it passes through the shaping means of the stapling device.

Figure 38b is a cross-sectional view of the staple wire after it passes through the shaping means of the stapling device.

Figure 39 is a detailed cross-sectional view taken on line 39—39 in Figure 38.

Figure 40 is a detailed plan view of the means shown in Figure 38 in position for cutting and bending the staple wire.

Figure 41 is a detailed cross-sectional view taken on line 41—41 in Figure 40.

Figure 42 is a section similar to Figure 38 showing the wire staple completely formed for attaching the string to the bag.

Figure 43 is a detailed plan view of the string severing means.

Figure 44 is a detailed cross-sectional view taken on line 44—44 in Figure 43.

Figure 45 is a detailed elevational view of the bag discharge transfer means corresponding to a section taken on line 45—45 in Figure 33.

Figure 46 is a detailed plan view corresponding to a section taken on line 46—46 in Figure 45.

Figures 47 and 48 are detailed sections taken on lines 47—47 and 48—48, respectively, in Figure 45.

Figures 49 and 50 are front elevational sections showing the bag transfer means corresponding to views taken on lines 49—49 and 50—50, respectively, in Figure 33.

Figure 51 is a detailed fragmentary view of the connecting transmission from the drive to the swinging means for said discharge bag transfer shown in Figures 49 and 50.

Figures 52, 53, 54 and 55 are fragmentary top elevational views showing successive positions of the string handle looping the tag positioning means.

Referring in detail to the drawings and particularly to Figures 1 to 11, inclusive, 60 denotes generally a complete full automatic machine constructed to embody the invention and comprising in combination cooperating apparatus, devices and mechanisms for making complete tea balls M of the pillow type with stapled string handles S and tags T or the like articles on large scale production.

As seen from Figure 1, said machine 60 comprises a tea supply feed measuring mechanism A which provides successive charges of predetermined quantities of tea to bags M1 made by an apparatus B which receives cloth for making said bags M1 of cut unit sections M2 from a tubular cloth strip M3 of a suitable supply C.

The bags M1 after being filled with tea by a hopper 64 are transferred to apparatus D for sewing the top closure seam O. The closed bags M4 are next operated upon by a string handle and tag applying device E to anchor one end of each string handle S to bag M4 at the top closure seam O, the finished bags M finally being trans-

ferred to discharge apparatus F with the string handles S and tags T in non-tangling position ready for packing in shipping containers (not shown).

All the parts of machine 60, namely, the measuring feed mechanism A, bag making apparatus B, bag cloth supply C, top closure apparatus D, string handle and tag applying device E, and discharge apparatus F, are interconnected in co-operating timed relation by suitable driving and power transmission means G. This driving and power transmission means G is controlled through the operation of a hand shift lever 65, the interconnecting portions of which by a suitable clutch control 65d can selectively operate the machine 60 in conjunction with the string handle attaching device E or with the latter shut off, as will hereinafter be described.

The tea supply feed measuring mechanism

The mechanism A may be constructed of parts assembled to operate in the manner similar to that disclosed in Patent No. 2,015,017, granted September 24, 1935, by Louis Hirschhorn and Hans Irmscher and is seen to comprise a tea storage receptacle 61 in which the bulk of the tea supply is stored. Said receptacle 61 has extending diagonally therein a stirrer 61a which is intermittently driven through a ratchet drive 61b. The latter is actuated by a crank and lever drive 61c which in turn is operated from a cam mechanism 61d. A bell crank and linkage 61e is also driven by said cam mechanism 61d for operating the ratchet tooth roller drive 61f to feed the tea from said receptacle 61 to a conveyor 61g which empties into an auxiliary feed receptacle 62a of an agitating means 62. The stirrer 61a, ratchet tooth roller drive 61f and the conveyor 61g serve to break up any mass or lumps of tea so that the latter is fed to said receptacle 62a in a loose, freely flowing stream. Said conveyor 61g is driven through a ratchet wheel drive 61h which interconnects with the bell crank and linkage 61e.

The auxiliary receptacle 62a is provided with converging bottom walls, one of said walls being formed by a slideable bar 62b which rests upon the backing plate 62c, the other of said walls by a swinging bar 62d secured to a lever 62e. The swinging bar 62d moves in the path of flow of the tea and when swung upwardly into the auxiliary receptacle 62a keeps the tea from escaping therefrom, said bar 62d being provided for this purpose with an arcuate shaped extension gate 62f which moves in position to shut off said flow. The bar 62d is swung back and forth in unison with the movement of the linkage 61e, and the bar 62b is actuated through the linkage 62k and cam 62j for slideable movement back and forth upon the supporting plate 62c.

The receptacle 62a empties into a flexible conduit 62g which is vibrated by a shimmerying motion to prevent the tea from clogging therein, and serves as positive feeding means to the restricted inlet of a rotary measuring device 63. The shimmerying motion of said conduit 62g is provided through a cam transmission 62h driven by a vertically extending drive shaft 66 which also drives the cam 62j and the cam 61d of the receptacle stirrer 61a.

The lower end of said drive shaft 66 is formed with the crank portion 67 which through a reciprocating rack 68 rotates the measuring device 63 so that a predetermined amount of tea is taken from the flexible conduit 62g and de-

livered to a feed hopper 64, all in the manner described in detail in the aforementioned patent application.

The drive shaft 66 below the crank portion 67 carries a drive cam 165 for operating a shear 10 to sever the interconnecting thread stitches formed between successive bags M4 after the top closures O have been applied by a sewing machine 153 in the manner hereinafter described.

Said drive shaft 66 below said cam 69 is terminated by a bevelled gear drive 71 which connects with a jack shaft 72, the latter being driven through a pair of helical gears 73 by a main power shaft 74. Said main power shaft 74 may be driven by a motor or other suitable power source (not shown) through a belt 65a and said clutch control 65d.

It is also desirable to provide between the cam 69 and the bevel gear drive 71 a clutch 208 having an operating handle 209 which serve to selectively cut off the operation of the tea supply feed measuring mechanism A. Said clutch 208 may be of any well known construction and preferably being of the friction or spring pressed contacting surface type which is adapted to yield should any obstructions such as a nail pass to the measuring device 63. By operating said handle 209, the entire mechanism A driven by said vertical drive shaft 66 and the crank portion 67 is made inoperative, the remaining apparatus, devices and mechanisms forming machine 60 may be operated and are controlled through the lever 65 as described above.

The vertical drive shaft 66 has a semi-circular housing 66a which extends therearound and is bolted to the top of frame H of machine 60. This housing 66a serves as guard to shield the said shaft 66 and the moving parts driven thereby, and also supports a top bearing 66 of said shaft.

Bag cloth supply and feeding mechanism

Referring now to Figures 1, 2 and 5, the cloth supply C may be enclosed in a container 80, the tubular cloth strip M3 preferably being flat rolled and is unwound by passing out through a slot 80a provided in the container 80 and around a suitable projecting guiding pin 82 which extends from the frame H of the machine 60. Said strip M3 is then fed to the bag making apparatus B by means of a reciprocating cloth feeding mechanism 83.

As seen from Figures 1, 2, 5 and 6, the cloth feeding mechanism 83 comprises reciprocating gripping means formed by a jaw 83a and a bar 83b cooperating therewith which clamp the strip M3 during its lowest or retracted position and on moving up draws the strip M3 from the container 80, unwinding same to feed an amount to the bag making apparatus B sufficient to make a single bag. The jaw 83a and bar 83b of said gripping means are carried on the free end 83d of a cam lever 83c, the inner end 83e of said lever 83c cooperating with a cam 83f which is seen to turn with a main cam shaft 84. Said cam lever 83c is fulcrumed on bolt 83g supported on a bracket 83h which extends from the frame H.

The fulcrum bolt 83g is adjustable along the cam lever 83c so that the movement of the lever can be varied for supplying a desired length of the strip M3. By this simple adjustment and another of equal simplicity hereinafter described, the size of the bag made by the machine 60 may be varied, this variation resulting in shortening or lengthening the depth of the bag.

Now referring to Figures 6, 16, 17 and 18, it is seen that there is pivotally attached to move with the lower end 83j of cam lever 83c a vertically extending connecting rod 83k, the upper end 83m of which is pivotally connected to a vertically slideable frame member 83n. Said member 83n is guided in its movement by a vertically extending rod 83o which is engaged by the slide bearing block 83p extending from said frame 83n.

10 The free end 83d of lever 83c carries a vertically extending bar 83r, the upper end of which slides in a bracket 83s having a suitable screw adjustable friction tension means 83t to control the reciprocating movement of the mechanism 83 in order that the same may operate smoothly.

The frame 83n has mounted thereon a pair of clamping feed rollers 83u which cooperate with the jaw 83a and bar 83b of the cloth feeding mechanism 83 to feed the bag strip M3 from the container 80 to the bag making apparatus B. Said rollers 83u are journaled on clutch shafts 83v which permit each of the rollers 83u to rotate only in one direction, the rotation taking place on the downward movement of the frame 83n.

20 Each shaft 83v, as shown in Figure 18, comprises a pivoted spring pressed clutch pawl 83w which engages the counterbored annular surface 83i of the feed rollers 83u for eliminating any possible free turning movement of said rollers 83u. A friction belt 83x is threaded to extend between said rollers 83u for eliminating any possible free turning movement of said rollers 83u. Said belt 83x may be anchored at one end at a bracket 83y extending from the frame 83n, the other end thereof is provided with a tension spring 83z which may be secured to the machine frame H.

Suitable interconnecting guides 83l mounted above and below the rollers 83u may be provided for retaining the cloth strip M3 in proper alignment with relation to said rollers 83u.

Extending through the leading end of the tubular strip M3 and engaging between the rollers 83u there is a tongue member 85 having an enlarged upper portion 85a which may be cut away along its opposite edges at 85b so as to be slightly narrower than the width of said bag strip M3. The portion 85a of said tongue member 85 is gradually tapered downwardly in thickness for a short length to provide a relatively thin flexible portion 85c in the remainder length thereof to extend a distance below the rollers 83u, as shown at 85d in Figures 16 and 17, the enlarged portion of the tongue 85a being limited in its downward movement with respect to the tubular bag material M3 by a pair of spaced rods 85e.

The portion 85c of tongue member 85 passing within said strip material M4 and between the rollers 83u is formed with an S-shaped bend to retain the tongue member 85 within said material M3 to permit movement of said material with respect thereto in the following manner. The upward movement of the slideable frame 83n takes place while the jaw 83a and the bar 83b grip the strip material M3 together with the tongue portion 85c therein. Just prior to the upward movement of said frame 83n, shear blades 86 complete the severing of the upper portion or bag section M2 from the strip material M3 which is to form a single tea bag. The shear blades 86 thereafter open up to permit the passage therethrough of said strip material M3 gripped and carried by the frame 83n carrying within said material M3 the tongue 85, said material M3 then 70 moving from a lower position below the shear

blades 86 to the fully raised position above said blades 86 as shown in Figure 17.

The strip material M3 at this extreme raised position will be engaged and held by suitable means forming part of the bag making apparatus B hereinafter described and the frame 83n will thereafter start in its downward movement. During this downward movement, the rollers 83u are released for rotation and ride along the outside of the strip material M3 which is held by its upper end against return movement. Due to the S-shaped form of the tongue member 85 retained between the rollers 83u, said tongue member 85 will be retracted within the material M3 and will move in unison with said rollers 83u until the enlarged end 85a again takes the position below the shear blades 86, as shown in Figure 17. At this time the frame 83n has arrived at its lowermost position and the strip material M3 above the enlarged tongue 85a is then again free to permit the severing thereof by the shears 86 to form the bag section M2.

As said bag material M3 before being cut is projected up beyond the end of the enlarged upper portion 85a of the tongue member 85 and the shear blades 86, said enlarged tongue portion 85a spreads open the upper end of the bag material M3 sufficiently to permit the same to be drawn over spaced fingers 90 which are in parallel alignment with the wide sides thereof extending in the same plane, as shown in Figures 16 and 17. These fingers 90 are rotatably mounted about spaced axes passing through the length thereof by means of shaft portions 90a which are journaled in cooperating toothed segment member 91. Said segment members 91 are pivotally mounted on stud shafts 92 which are spaced and extend in parallel relation to a radial axis X-X of a horizontally disposed turntable frame 93 (see Figures 5, 16, 17 and 21).

As seen from Figures 16 and 17, the segment members 91 carry upstanding posts 91a which are interconnected by a tension coil spring 91b. This tends to keep the fingers 90 in extended spread position, namely, in substantially parallel alignment, and is sufficient to put a slight strain on the material of the bag when engaged thereon. The turning of segment members 91 for moving the fingers 90 to and from each other is accomplished by means of a movable arm 120 which is pinned at the end of a vertically extending rod 121. The lower end of said rod 121 is extended and is pivotally secured to a cam lever 122 which has a cam roller 122a cooperating with a cam 122b, the latter being secured to a cam shaft 84, the lever 122 being fulcrumed on the ack shaft 113 (see Figures 5, 6 and 16).

The movable arm 120 is operated through said cam 122b and said interconnecting lever 122 and rod 121 for projecting it in the path of movement of an extending portion 91c integrally formed with the segment 91. The arm 120 serves to press said portion 91c for swinging the segments 91 which are interlocked through teeth 91d against the action of the spring 91b to bring the fingers together so that they will readily enter the open upper end of the cloth M3. This action takes place at a hereinafter called "first station" where the bag strip material M3 is fed to the turntable assembly forming the bag making apparatus B.

The turntable frame 93 is in the form of a spider having a hub 93a which is secured to rotate with a vertical shaft 94, the latter being journaled in the spaced upper and lower ball bearings 95. The lower ball bearing 95 is supported by a

cross tie plate 96 and the upper bearing 95 on an angle bracket 97 which are carried by the machine frame H. Adjacent to the upper bearing 95 carried by the angle bracket 97 and below the frame 93, there is provided a gear wheel 98 secured to turn with said hub 93a. Said gear wheel 98 meshes with a pinion 99 supported on a bracket 100a extending from an upper horizontally extending arm 100b which turns on shaft 94 and also has bolted thereto an upright support frame 100, as shown in Figures 5 and 20. Said arm 100b and a similar lower horizontally extending arm 100c spaced therefrom support said frame 100 for free turning movement on the shaft 94, said arms 100b and 100c being assembled to fit between the cross tie plate 96 and angle bracket 97, as shown in Figure 5.

Referring now to Figures 2 and 20, the pinion 99 is seen to be driven by means of a flexible shaft drive 101. The lower or drive end of said shaft 101 comprises sprocket wheel 102 which is connected through a linkchain 103 with an intermediate idler sprocket 104, the latter being mounted to turn on shaft 105. Said chain 103 is driven through a sprocket 106 mounted to turn with the vertically extending shaft 66 (see Figure 2), the latter being driven through the bevelled gears 71 as shown in Figure 5.

The spaced fingers 90 carried by the spider frame 93 are adapted to rotate vertically through an arc of 90 degrees so that said fingers 90 can swing from a position of alignment of the flat sides in the same plane as shown in Figures 16 and 17 to an alignment with the flat sides in parallel planes as shown in Figures 19 and 20 for opening the bag M1 to receive a charge of tea. To accomplish this rotary movement, short crank arms 90b are provided and disposed at different levels, said arms being pivoted to turn with the shaft 90a, as shown in Figure 16, one of the crank arms 90b of each pair of fingers 90 (the one on the right) is located just below the level of stud shaft 92, and the other (on the left) is located above stud shaft 92. As seen in Figure 21, these crank arms 90b are connected to opposite ends of a forked member 90c, the bent middle portion of said member 90c engaging around pivoting pins 90d which extend up from cam levers 90e. The latter are pivoted at 90f uniformly on the rim portion of the spider frame 93 to permit swinging the free ends thereof which carry rollers 90g to ride in a cam groove 107a of a relatively stationary cam member 107. Said cam member 107 is supported on the hub portion 93a of the spider frame 93 but is retained against rotation by the upper end 97a of the angle bracket 97 secured to the cross plate 96 which in turn is supported on bed frame H (see Figures 5 and 12).

The upright support frame 100 carries gib mounting 108 for adjustably carrying a sewing machine 109, said frame 100 with the gib mounting 108 oscillates to permit the advancement of the needle 109d of sewing machine 109 while applying a stitch seam closure Q at the bottom of the cloth bag section M2 in the manner herein-after described. Said machine 109 is driven through a pulley 109a, a belt 109b which runs over two angularly disposed idlers 110, and a drive pulley 109c, the latter being mounted to turn with the main drive shaft 74, all as shown in Figures 2, 5, 6 and 12.

The oscillating of the support frame 100 together with the sewing machine 109 about the shaft 94 carries the pinion 99 permitting the sew-

ing machine 109 to accompany the bag sections M2 during the seam sewing operation. As seen in Figure 12, said oscillation is accomplished by providing a connecting bar 111 which has one end pivoted 111a to the sewing machine 109 and the opposite end connected through a ball and socket joint 111b with a bell crank 112, said bell crank opposite the ball and socket joint 111b being terminated by roller 112a which rides on a cam 114, the latter being keyed to turn with a cam shaft 84. A tension spring 115 keeps the roller 112a pressed against the cam 114, as is clearly shown in Figures 5 and 6.

Before the bag M1 with the bottom seam sewn closure Q reaches the filling or charging station, the thread interconnecting the bottom seams Q of the adjacent bags M1 is severed. For this purpose there is provided a suitable shearing or severing means 116. As shown in Figures 12 and 13 said severing means 116 consists of a stationary blade 116a and a movable blade 116b, which is pivoted on screw 116c carried by a suitable bracket 116j which extends from the machine frame H. The end 116d opposite the cutting edge of said shear blade 116b connects with a rod 116e. The latter pivotally connects with a cam lever 116f which carries a roller 116g riding on a cam 116h, said cam being pinned to turn with the cam shaft 84 (see Figures 5 and 6).

The movement of each bag M2 through the sewing machine 109 is a continuous one and as the needle 109a thereof ceases to pass through the bag material, it forms a strand of chain stitches J until the next successive bag M2 is brought to said needle by the fingers 90. As the sets of fingers 90 are spaced close together the distance between two successive bags M1 leaving the sewing machine 109 is only sufficient to permit the passage of the blades of the severing means 116. The severing of the interconnecting strand J is such that there is practically no necessity for trimming the bags M, the seam Q terminating substantially with the end of the material of the bag M1.

The machines 109 and 153 each require two yarns or threads which are supplied from four spools 210 carried on a cage bracket 211, the latter being supported from the machine frame H as shown in Figure 1.

The means for mounting the strip material M3 to the fingers 90 and severing the bag section M2 is accomplished through the cam 116h (see Figures 6 and 12) which serves through coaction with a branch arm 116k extending from the said lever 116j to actuate a rod 117 connected therewith and pivoted thereto at 117a. The end 117b opposite said pivot 117a operates a gripping means denoted generally at 118. (See Figures 16 and 17.) Said gripping means 118 has spaced jaws 118a formed on the extremity of a T-shaped member 118b. The end of member 118b opposite the jaws 118a being pivoted on stud shaft 118c carried by a bracket 118d which is rigidly supported from a relatively stationary part of the machine frame H.

The gripping means 118b is loosely mounted on the stud shaft 118c and when effective is pressed by a spring 119 carried by a hub 119a of a lever 119b, the latter being pivoted on the stud shaft 118c. Said lever 119b has an arm 119c extending therefrom which is pivotally connected to the upper end of the rod 117 as is shown in Figures 12, 16 and 17. The hub 119a carries a pin 119d which is adapted to engage the T-shaped member 118b for retracting the gripping jaws 118a to release the upper end of

the cloth M3 from engagement between said jaws 118a and the fingers 90.

The upper end of the bag strip material M3 after being retained in place by the gripping jaws 118a is severed by the shear blades 86 as shown in Figures 16 and 17. Said shear blades are pivotally mounted on a bolt 86a which is carried by a support 97c extending from the angle bracket 97. The power end 86b of the blades 86 are connected through a twisted link 86c and a double linkage 86d to a pivot bolt 86e carried at the end of the bar 86f which is secured by any suitable fastening means such as screw fastening 86g mounted on a rock shaft 86h. The bar 86f has an outwardly extending cam lever 86j which terminates in a roller 86k riding in a grooved cam 86m, the latter being secured to turn with the cam shaft 84 as shown in Figures 2, 5 and 12.

On the operation of the shear blades 86, the upper end of the strip material M3 is severed leaving a bag section M2 carried by one pair of the fingers 90 of the turntable apparatus B. The fingers 90 as they rotate move the lower open end of the bag section M2 onto a presser foot 124 which has a trough shaped portion 124a, the bottom surface 124b of which is slightly inclined upward with relation to the movement of the sections M2. This portion 124a and surface 124b are so designed and constructed as to positively contact the lower edges of bag section M2. The outer end of the inclined portion 124a terminates in a tail piece 124c wherethrough the machine needle 109d extends. In order that said needle may form an overlocked stitch seam by said machine 109, the presser foot 124 may be attached to the sewing machine by any suitable means such as bracket 109e and may be resiliently supported through a spring mounting 124d. Behind the presser foot 124 is a feed dog 125 which has a slot 125a wherethrough the needle 109d extends in register with the tail piece 124c.

The turntable apparatus B has a step by step movement, the "first station" being located to take advantage of one of the times when the parts of said apparatus are not rotating, that is, when they are stationary. The bag section M2 as it leaves the said "first station," passes on to the "second station," namely, to the sewing machine 109 where the bottom open end has the overlocked seam Q applied thereto. While the fingers 90 of the turn table apparatus B are in motion and also while they are stationary in said step by step movement, the sewing machine 109 is swung to move with the bag sections M2 as they advance during the sewing operation by a swinging of the support frame 100 through the means already described, and by said means said machine is also swung in a counter direction to the advance movement of the bag sections M2 while the latter are stationary during said step by step movement. The to and fro movement of the machine 109 is so timed with relation to the step by step movement that said sewing machine 109 continues to apply seams Q on consecutive bag sections M2 without stopping or interruption, in regular sequence.

The fingers 90 of the turntable apparatus B with the bags M1 in their rotation after passing the "second station" arrive at the "third station," namely that where the bags M1 are filled one at a time through the upper or open end thereof. As seen from Figures 19 and 20, the moving parts of turntable apparatus B during this filling operation are in a relatively stationary

position of said step by step movement which permits intermittently the moving of the strip material M3 onto the fingers 90 at the "first station" and also the cutting of the thread stitches between successive bags M1 by the shears 116 through the operation of the parts already described above and shown in Figures 12 and 13.

At the "third station," fingers 90 have moved to position the wide sides thereof in parallel alignment, thereby opening up the bag M1. This movement as has been described above is caused by the cam 107 and the cam levers 90e to swing the fingers 90 on their vertical axes from the position shown in Figures 16 and 17 to that shown in Figures 19 and 20. The bag M1 on the fingers 90 then being open, permits the lower spout portion 64a of the hopper 64 to enter therein. This spout portion 64a is raised and lowered by means of a horizontal arm 64b which in turn is secured to move with a vertically extending rod 64c the lower end of which is connected to a cam lever 64e, the latter being pivoted at 64f on a horizontally extending auxiliary shaft 126. The mid-portion of said cam lever 64e carries a roller 64g which rides on a cam 64h, the latter being secured to turn with the cam shaft 84, as shown in Figures 6, 19 and 20.

The rotary measuring device 63 connects with the spout portion 64a through the hopper 64 and in order that said portion 64a may clear the moving parts carried by the turntable apparatus B when the latter is in motion there may be provided suitable aligning guiding means, such as for example, a slot plate 64j which engages the collar 64k on the arm 64b. The cam timing due to the plate 64j is such that the spout portion 64 enters the bag M1 simultaneously with the release of a charge of tea by the measuring feed device 63. The moving parts of apparatus B remain relatively stationary at such time to permit the tea to pass through the hopper spout 64a and into the bag M1. The spout 64a is then retracted by the camming action and the upward movement of the rod 64c aided by the cam 64h through the connections described above.

In order that the bag M1 may be in the properly aligned position for filling, there is provided a stationary arcuate shaped guide or rail 127 which is supported by a bracket 127a from the frame H. Below the rail 127 there may be provided an open container 128 for receiving any spillage from the spout 64a or from any damaged, torn or defective bags M1 positioned under the rotary measuring device 53. (See Figures 19 and 20.)

As shown in Figure 5, to protect the moving parts of apparatus B, a cover plate 123 is provided to terminate the upper end of the shaft 94, said cover plate being of sufficient diameter to 60 act as a shield for said parts. Said plate 123 may be secured in place by any suitable means such as bolt 123a.

Apparatus for sewing top closure

The bags M1 after they have been successively filled at the "third station" are carried by the turntable apparatus B which rotates to a "fourth station" where each filled bag M1 is transferred to the apparatus D for sewing the top closure seam O. The "fourth station" is shown in Figure 5 where the filled bag M1 arrives at a stationary position in the step by step movement of apparatus B on a line passing through the axis of apparatus B and apparatus D. The fingers 90 75

which at the "third station" were effective to hold the mouth of the bag M1 open and carry same, now at the "fourth station" are turned and swung together sufficiently to release the frictional engagement thereof with said bag M1. The weight of the filled bag M1 causes it to drop down into a gripping receptacle 129 of the top closure apparatus D positioned thereunder in readiness to receive same.

10 The gripper receptacles 129 each terminate an arm 130, said arms being mounted one above the other for independent rotation on a vertically extending center shaft 131. The gripper receptacles 129 however are positioned in the same horizontal plane as shown in Figures 5 and 25.

Each of the gripper receptacles 129 comprises a stationary outside wall 129a which has a lower end 129b thereof shaped to conform to the contour of a filled bag M1, and an inside wall 129c hinged by a suitable fitting 132 to the arm 130. (See Figures 22 and 23.)

20 The upper portion 132a of the hinge 132 has a downwardly extending rod 133 which is terminated by roller 133a adapted to ride on a cam 134. Said cam 134 comprises a center piece 134a having an outside surface guiding means 134b and an arcuate piece 134c, the latter having an inside guiding surface 134d. At the time when the filled bag M1 drops from the fingers 90 to the gripper receptacle 129, at the "fourth station," the roller 133a is riding on the outside surface 134b of cam piece 134a just before entering into engagement between the surface 134b and the surface 134d of piece 134c as indicated in Figure 25 at 134e. As the arms 130 rotate in a counter-clockwise direction, the roller 133a is moved radially inward causing the inside wall 129c to swing towards the stationary outside wall 129a gripping the filled bag M1 therebetween with the upper portion of the filled bag M1 extending beyond said walls 129a and 129c.

25 To insure the filled bag M1 being properly located within the gripper receptacle 129, there is provided suitable pusher means comprising a vertically upstanding wall 135 which is supported by a horizontally extending bracket 136, said bracket being mounted at a mid-portion thereof to terminate a rocking rod 137. (See Figures 22 to 24 inclusive.) The end of said bracket 136 opposite the wall 135 has pivotally mounted thereon a flapper 135a, said wall 135 and flapper 135a being effective to form end closures for the gripper receptacle 129 as is clearly shown in Figure 22. Thus when the filled bag M1 reaches the "fourth station" and said bag is dropped from the fingers 90 to the gripper receptacle 129, the wall 135 and flapper 135a are caused to move to an effective position for covering the opposite ends of the receptacle 129 to form end closures. The flapper 135a is also oscillated to push the filled bag M1 into the space wholly within gripper receptacle 129.

30 For operating said wall 135 and flapper 135a, the rod 137 is extended down and pivoted at 137a. (See Figure 5), the lower end of which being provided with a roller 137b which rides on the vertically disposed surface 138a of a cam 138, said cam shaft being pinned to turn with the cam shaft 84. (See Figure 5.) When the rod 137 is swung so as to bring the wall 135 and flapper 135a in effective position, the flapper 135a through a crank arm 135b engages a fixed stop 139 and causes the flapper to move towards the receptacle 129 against the action of a spring 135c which normally tends to swing said flapper 135a

away from the receptacle 129. It will be noticed that the cam surface 138a has protuberances 138b which serve to give the rocker rod 137 several quick successive in and out movements for tapping the bag M1 if necessary to locate the same within the receptacle means 129.

Each pair or set of fingers 90, of which there are sixteen sets uniformly spaced, as has already been described above, move in unison through operation of the mechanism shown in Figures 22 and 23 and are caused to turn with respect to each other and swing towards each other due to the action of the movement in the rod 90c and the engagement of the arms 91c cooperating with a cam means 140. In order to limit the separating or opening movement of the fingers 90 due to the action of the spring 91b, there may be provided the lug 91a which engages with the arm 91c and limits such opening movement.

The transfer of the bags M1 from apparatus B to apparatus D is accomplished with the aid of the cam means 140 carried at an upper end 141a of a vertically slidable rod 141, the latter being movably supported at 97c on the angle bracket 97. As shown in Figure 6 the lower portion 141b of the rod 141 is pivotally connected to a horizontally extending arm 142 and is mounted to rock on the auxiliary shaft 126. The arm 142 carries a roller 143 which rides on a cam 144, the latter being mounted to turn with the cam shaft 84. As the fingers 90 carrying the filled tags M1 arrive at the "fourth station" the rod 141 is raised to engage the cam 140 with the arm 91c of the segment member 91 for swinging the fingers 90 towards each other permitting the filled bags M1 to successively drop down into the gripper receptacles 129 as described above.

In order to rotate the arms 130 with the receptacle means 129 about the vertical shaft 131, there being eight such provided as shown in Figure 25, a ring drive 145 comprising a wheel rim 145a which carries uniformly spaced thereon bell cranks 145b, each pivoted at 145c, said bell cranks 145b each carry a roller 145d which rides in a fixed cam slot 146. Spaced from the roller 145d, each bell crank has a yoke or fork portion 145e which is adapted to engage with a roller 130a extending down from the arm 130. The ring drive 145 has a spider portion or spokes 145f carrying said rim 145a which turns with the shaft 131. The shaft 131 at its lower end 131a is terminated by a flange 131b which is secured in a hollow off-set hub 147a on a gear wheel 147, the latter engaging with a pinion 147b which is mounted to turn with the shaft 105. Said pinion 147b and shaft 105 are driven through the sprocket 104 and chain 103 as hereinbefore described. (See Figure 2.)

As seen in Figures 2 and 5, the shaft 131 is journaled in a hub portion 134f of the cam 134, said portion 134f having a flange 134g carried on a cross member H1 of the frame H by means of cradle member 148 which is pivotally secured to the flange 134g at diametrically opposite portions thereof through pointed screws 149. The cradle 148 connects with the cross frame H1 through a flat spring 150 which is bolted to the latter at 150a and pivoted to the cradle member 148 at 150b. A fitted portion 148a of the cradle member 148 connects with an arm 148b, the latter having an elongated slot end 148c which has passing therethrough a bolt 148d extending into the frame H as shown in Figures 1 and 2. By adjusting the slotted arm 148b with respect to the bolt 148d, the entire mechanism assembled on the shaft 131

can be raised or lowered to suit the conditions of operation and particularly to enable the machine to handle various heights, that is, sizes of bags M1. This simple adjustment and that of fulcrum bolt 83g on cam lever 83c as already described is all that is required to change from one size of bag to another.

Terminating the upper end 131c of the shaft 131 is a cover plate 151 which is retained by a bolt 152 to turn with the shaft 131. Said cover plate 151 serves as a guard or shield for keeping out foreign matter or interfering with the moving mechanism of apparatus D below.

The filled bags M1 are successively carried by the gripper receptacles 129 and arms 130 from the "fourth station" into the path of an overlocked stitching sewing machine 153 which may be similar in construction to the machine 109. This machine 153, however, is normally stationary but is pivoted to permit moving the needle 153a thereof out of the effective position for adjustment or repairs. To this end, the machine 153 is supported in a gib mounting 154 having a side plate 154a which is extended by a portion 154b beyond the lower side 153d of the sewing machine 153.

The portion 154b is pivoted at 154c to a bracket 155 which is bolted in an upright position on the frame H. See Figure 26. The lower end 154d of the gib mounting 154 is provided with an abutment plate 154e which bears on the upper end 156a of a compression spring 156, the lower end 156b of which is held in place by a retainer boss 157 formed on the bracket 155. A set screw stop 158 is threaded through the bracket 155 for adjusting the sewing machine 153 with respect to the side plate 154a.

Extending from said plate 154a through a slot 155a of the bracket 155 is a stud 155b provided with a nut and washer 155c. Normally the spring 156 tends to swing the machine 153 on the pivot 154c so that the needle 153a thereof is in a lowered position, that is, with the lowest end of the slot 155a embracing the stud 155b to adjust the machine 153 to the proper height and position for applying a top overlocked stitched closure seam O to the upper end of the filled bag M1, the machine 153 is tilted against the action of the spring 156 and held rigidly in place by tightening the nut and washer 155c on the stud 155b.

Adjacent the bracket 155 is a small pivoting support 159 which has one end 160a of a bar 160 bolted thereto. The upper end 160b of said bar 160 carries a pair of guide pulleys 161 over which the machine belt 162 runs. This belt, as shown in Figures 2 and 26, drives the sewing machine pulley 153c and extends down through the frame H and is driven by a pulley 162a, located adjacent the pulley 109c which turns with the shaft 74, as shown in Figure 5. The machine 153 is provided with a presser foot 163 carried by a bracket 164 from the sewing machine 153, a feed dog 153b, and a spring 153d for holding the presser foot 163 against the filled bag M1.

As each bag M1 is fed through the sewing machine 153 it passes along the inclined surface 163b of the trough 163a and the edge portions at the top opening thereof are brought into proper position for sewing the overlocked stitch by the needle 153a. The movement of the bag M1 is continuous and as the needle 153a ceases to pass through the bag material it forms a strand of chain stitches R until the next successive bag M1 is brought to the needle 153a by one of the arms

130. The cam groove 146 is so designed that the filled bag M1 as it leaves the "fourth station" in its approach towards the sewing machine 153, is given a relatively fast movement so that the successive arms 130 are brought close together, the distance between the bags M1 being such as to form the shortest possible interconnecting strand by the stitches R as seen from Figure 25.

As the bag M4 with the top opening closed by the overlocked stitched seam O applied by the sewing machine 153 leaves the latter and passes the shears 70, it is given a slight rapid movement so as to provide a tension on the interconnecting strand formed by stitches R. This tension is desirable to facilitate the cutting by the shears 70 which must be quickly effected since the arms 130 at all times are in continuous motion.

The shears 70, as shown in Figures 25 and 28 to 32, inclusive, are bolted to the housing 66a by a bracket 70a which pivotally connects with one end 70b of a lever 70c. The middle portion of said lever 70c has a roller 70d which rides on the cam 165, the latter being mounted to rotate with the vertical shaft 66. This cam 165 has a notch portion 165a into which the roller 70d enters due to the action of the tension spring 70e which has one end thereof anchored to the sewing machine bracket 155 and the other secured to the end 70f of lever 70c. Said end 70f terminates in an arm 70g which carries a bolt 70h for securing thereto a stationary blade 70j of said shears 70. Also mounted for rotation on said bolt 70h there is a sleeve member 70k to which is fastened, by any suitable means such as a key 70m, a cutter 70n for cooperating with the blade 70j. The sleeve member 70k has a projecting portion 70p which cooperates with a fixed stop 70q, the latter terminating a strap 70r which is bolted to project from the sewing machine bracket 155. There is also provided a coil spring 70s which has one end thereof secured to the sleeve member 70k as at 70t, the other end of which is anchored to the arm 70g at 70u. Said arm 70g also has pivoted thereto a latch 70w which has the catch 70x thereof adapted to engage a ledge 70y provided on sleeve member 70k.

Thus in the movement of the shears 70 as a unit to and from the bags M4, due to the roller 70d entering and leaving cam notch 165a, simultaneously causes the projecting portion 70p to move away from the stop 70q during the movement of said shears 70 toward the bags M4 for tripping the catch 70x to release the cutter 70n. The latter then is activated to sever, that is, snap, the tensioned strand R. On the return movement of the shears 70, the stop 70q moves to abut the projecting portion 70p and the spring 70s acts to swing the cutter 70j to its open position. The catch 70x is then permitted to engage the ledge 70y to retain the same until again released. Said catch 70x has a counterweight portion 70z which tends to permit the catch 70x to move by gravity into said engaging position.

The distance between two successive bags M4 as they leave the sewing machine 153 is only sufficient to permit the passage of the shears 70 and the severing of the tensioned interconnecting strand R is such that there is practically no necessity for further trimming the bag M4. The seam O thus terminates substantially with the end of the material from the bag M4.

The parts are so designed that the snipping movement of the shears 70 takes place during the travel movement of the shears 70 towards the strand R, that is, when the roller 70d enters

the cam notch 165a, the arm 130 carrying the bag M4 moves in advance of the shears 70 with a quick motion due to the action of the cam groove 146 to a "fifth station" where the stapling of one end of the string handle S to the bag M4 is done by the string handle applying device E.

String handle applying device

Referring now to Figures 1 and 34 to 43, inclusive, and more particularly, Figures 34 and 38, the closed bag M4 on arriving at the "fifth station," enters between a fixed punch jaw 166 and a cooperating movable jaw 167 of a string handle applying device E, said fixed jaw being bolted to a frame portion 168 which also serves as a support for the movable jaw 167.

The fixed jaw 166 carries an anvil or die 166a which has an extension portion 166b for guiding said bag M4 to enter into proper position for the stapling operation. Said die 166a cooperates with a central plunger or setter 167a and staple formers 167b of the movable jaw 167. Said formers 167b extend along on opposite sides of the setter 167a, the latter being carried by a cross head 167c which reciprocates in a slideway 168a provided in the frame portion 168. Also mounted for movement in said slideway 168a below the cross head 167c is a second cross head 167d having an upstanding support 167e which carries the formers 167b, said support 167e acting as a bearing for the setter 167a. In order to keep said former and setter in position, a tie plate 167f is provided which is bolted to upstanding support 167e by means of screw 167g.

The leading end 167h of the movable jaw 167 is preferably made with a hardened plate which has a half round groove 167j extending therein at right angles to the path of movement of the setter 167a and formers 167b. Said end 167h also has passageway 167u therein which permits the setter 167a and formers 167b to pass therethrough across the groove 167j for shaping and applying the staple in the manner hereinafter to be described.

The groove 167j connects with one end 169a of a curved conduit 169, the other end 169b of said conduit being extended to receive a strand of wire W which has been rolled between a knurled wheel 171 and a smooth roller 172. The conduit 169 may be bolted to the frame of the device as at 169a. In the passage of the wire W between said wheel 171 and roller 172 it is changed from a circular shape as shown in Figure 38a to a flattened shape, as shown in Figure 38b.

The wheel 171 and roller 172 turn with shafts 171a and 172a, respectively, the drive for said shafts being supplied by the meshing gears 171b and 172b. Said gears are loosely meshed so that the space between the wheel 171 and roller 172 may be adjusted. To this end, the shaft 172a is pivotally mounted at its lower end 172c to the extension piece 171c. The latter is bolted to a third cross head 167k which is disposed in the slideway 168a aligning with and below the cross head 167d, as shown in Figure 35. This cross head 167k carries the movable jaw 167 as a unit, the leading end 167h of which is secured to the cross head 167k by any suitable means such as bolts 167m. Said bolts 167m also serve to hold a cover plate 167n which is fitted to extend over the leading end 167h. See Figure 43. The wire W is supplied to the wheel 171 and roller 172 from a suitable source (not shown) through a conduit 173.

For turning the gears 171b and 172b, there is mounted on the shaft 171a, a ratchet wheel 171d below the gear 171b which is actuated by a spring pressed pawl 171e which in turn is carried on a bracket 171f. Said bracket has extending therefrom a roller 171g which rides in a cam slot 171h of a cam plate 171j. The bracket 171f is pivotally mounted on the lower end 171k of an arm 171m, said arm projecting from the extension piece 171c and preferably made integral therewith. Thus on movement of the cross head 167k and as effected by the camming of the roller 171g, the pawl 171e is caused to actuate the ratchet wheel 171d and turn the same for feeding a predetermined length of wire W to form a staple P in a manner hereinafter described.

The cam plate 171j has one end 171n pivoted to the extended portion 167p of the cross head 167k. The other end 171p of the cam plate 171j connects through a ball socket connection 171q with a rod 171r, the lower end 171s of which connects with one side of a cam 174 through a bell crank connection 171t. Said cam 174 is secured to turn with the cam shaft 84, as shown in Figures 1 and 10.

The cam plate 171j is caused to oscillate up and down on pivot bolt 171u located at the cam plate end 171n by the movement of a rod 171r. This movement of cam 171j causes a roller 167q which is carried by the cross head 167d of the formers 167b to move in a cam slot 171v of the plate 171j so that said former 167b reciprocates in the passageway 167u when the leading end or block 167h of jaw 167j and said former 167b move to and from the fixed jaw 166. Simultaneously a roller 167s, which is carried by the cross head 167c of the setter 167a is caused to move in a cam slot 171w of the plate 171j for reciprocating the setter 167a. The oscillation of said cam plate 171j also simultaneously causes a roller 167t carried by the cross head 167k to move in a slot 171x of the plate 171j which reciprocates the entire movable jaw 167 as a unit to and from the fixed jaw 166, the cam plate 171j itself being mounted to move with said movable jaw 167.

Now referring to the drawings, Figures 38 to 43, inclusive, the stapling operation will now be apparent. With the parts assembled and positioned as shown in Figure 38, the movement of the rod 171r moves the cam plate 171j to first cause the former 167b to move from the position shown in Figure 38 to the position shown in Figure 40. This movement cuts off a length P or wire W equivalent to the outer distance between the two formers 167b, and as the leading ends of said former move past the groove 167j, the severed piece P or wire W is bent U-shaped about a shaping end 175a of a movable stop piece 175. Said stop piece 175 is pivotally mounted on a stud 175b carried on the end of the vertical knurled wheel shaft 171a and is normally pressed down in effective position by a spring 175c which is also mounted on said stud 175b. A ledge 175d on the tie plate 167f cooperates with an under side 175e which is mounted to move with the cross head 167d and acts to lift the stop piece 175 against the action of the spring 175c.

After the parts are in the position shown in Figure 40, further advance movement of the cam 171j causes the stop piece 175d to be raised against the action of the spring 175c and the shaping end 175a to be moved out of the path of forward movement of the now U-shaped formed staple P.

Still further advancing said cam 171j causes the setter 167a to move between the formers 167b for pushing said U-shaped staples P forward while all the cross heads 167a, and 167k also advance with the movable jaw 167 until the parts are in the position shown in Figures 42 and 44 at which time the setter 167a has forced the U-shaped staple P through the top edge of the bag M4, preferably just at or below the overlocked stitches forming the closure seam O. The ends of the staple P, through the action die 166a, are bent over towards each other, finally clamping an end string handle S by means of the staple P to the bag M4. This final clamping is accomplished at the end of the downward movement of the cam plate 171j. The latter is now moved up and brings in the parts back to the position shown in Figure 38.

Simultaneously with the completion of the stapling operation above described, while the movable jaw 167 is still in its fully advanced position against the fixed jaw 166, a chopper blade 176 which is pivotally mounted on a shoulder screw 176b projecting up from the plate 167n is swung across a path which engages and cuts the string handle S a short distance from the staple P as shown in Figures 43 and 44. The movement of said chopper blade 176 is accomplished through link 176c which has a pivoted end 176d connected to a bell crank 176e, said bell crank being pivoted at 176f to the extension piece 171c. The driven end of said bell crank 176e connects with an arm 176h through a link 176g (see Figure 9), said arm being pivoted at 176i which is mounted on a supporting bracket 177, which is bolted to the frame H. The arm 176h carries a holler 176k which rides in the cam slot groove 174a of the cam 174 on the side opposite thereof to the crank connection 171t.

After cutting the string handle S, as shown in Figure 44, the chopper blade 176 returns to the position shown in Figure 53, and the movable jaw 167 and the parts carried thereby return to the position shown in Figure 38 ready to make or apply a staple P to the next bag M4 as fed between the stapling device H. These cycles of operation are successively repeated automatically as each bag M4 is brought in position between the jaws 166 and 167 of the stapler.

During the return movement of said stapler parts, the wire W is automatically fed to the end or block 167h in predetermined lengths equivalent to that required to make one staple P. When this stapling operation has been completed, the finished bag M between the jaws 166 and 167 is released for passing to the "sixth station," that is, transferring the bag M from turntable apparatus D to a conveyor 188 of discharge apparatus F.

If desired, the transferring apparatus F may also serve to fold the string handle S and position the tag T terminating said handles so as to superimpose the tag T on the bag M. To this end a tag positioning mechanism N is provided for placing the completed tea ball M with the string and tag thereof in a non-tangling form on the said conveyor 188 ready to pack for shipment.

Bag transfer and tag positioning mechanism

After leaving the stapling device, the bag M is brought around on to a transfer and tag positioning mechanism N which consists of a pick up device 178 and a string manipulating means 179, the latter serving to position the tag T in a superimposed relation to the bag M.

As seen from Figures 33, 49, 50 and 51, the pick-up device 178 consists of a gripping tong 178a which has a cooperating lower jaw 178b extending from the end of a bell crank 178c which is pivoted at 178d from the end of a horizontally disposed bracket 178e which in turn is pivotally mounted on a vertically extending rod 178f. For rocking the tong 178a on the pivot 178d, the bracket 178c connects through a ball and socket joint 178g with a rod 178h. As shown in Figure 10, the lower end of said rod 178h connects with lever 178j which is pivoted on a common rock shaft 180. Said lever 178j carries a roller 178k which rides on a cam 178m, the latter being mounted to turn with an auxiliary cam shaft 181 which is driven through pinion 182a and gear wheel 182b. Said wheel 182b is driven by a pinion 182c which is secured to turn with the main cam shaft 84a.

Now referring again to Figure 49, coacting with tong jaw 178b is an upper jaw 178n pivoted at 178p thereon. The movable jaw 178n connects with an L-shaped link 178q which connects with one end 178t of a lever 178r which is pivoted at 178s on bracket 178o, as shown in Figure 51. Said lever 178r also connects at the other end 178u through a tie rod 178v with a lever 178w which is pivotally mounted on shaft 180, as shown in Figure 10. Said lever 178w carries a roller 178x which rides on a cam 178y which also is mounted to turn with the auxiliary cam shaft 181.

For removing the bag M from the gripper receptacle 129 and for raising said bag M so as to lie in a horizontal plane, there is provided an angle elevator member 183 which is mounted on the end of a lever 183a. As shown in Figure 49, said lever 183a is pivoted from a mid-portion thereof on a bolt 183b which is mounted to slide in cam slot 178z provided in bell crank 178c. The end 183c of lever 183a opposite said member 183 connects through a bolt pivot 183d with a bell crank 183e which through a ball and socket connection 183f joins a rod 183g to connect with lever 183h pivotally mounted on the shaft 180. Said lever 183g carries a roller 183i which rides on a cam 183j, the latter being mounted for rotation on the auxiliary cam shaft 181. See Figure 10. The bell crank 183e is pivoted at 183h on bell crank 178e. (See Figure 49.)

Referring now to Figures 50 and 51, the bracket 178e, which is mounted for turning movement on a stud 178f, has an arm 184 which through rod 184a pivotally connects with a sleeve crank 184c through a lever 184b which is made integral with the sleeve crank 184c, the latter being mounted to turn on a shaft 184d. Said sleeve crank 184c has spaced from the lever 184b an L-shaped arm 184e which carries a roller 184f riding on a cam 184g, said cam being mounted to turn with the cam shaft 84a.

The operation of the pick-up device 178 will now be readily understood. As the bag M reaches the tongs 178a, the upper jaw 178n closes through the action of the above described interconnecting linkage and the cam 178y grips the bag M at the upper closure seam O. During this closing movement, the angle elevator member 183 is drawn inwardly against the outer side of the bag M simultaneous with the gripping by the tong 178a through the interconnecting linkages and cam 183j. Thus the bag M is lifted from a vertical plane shown in Figure 49, in dotted lines, to a horizontal plane shown in full lines. Successive movements of said elevator member 183 are also shown in Figs. 53, 54 and 55. On

reaching this position the device 178 is rotated about the stud 178f as an axis through the action of the interconnecting linkages actuated by the cam 184g.

As the device 178 rotates on the stud 178f, the pivot bolt 183b of the lever 183a slides in a slot in 178z carrying the angle elevator member 183 along the underside of bag M so that when the bag M is swung in position directly over the conveyor 188 of the discharge apparatus F, said elevator member 183 has entirely cleared the bag M that is drawn beyond the inner edge portion thereof and the tongs 178a simultaneously released the grip on the top seam O of the bag. The bag M then drops onto the discharge belt 188 as is shown in Figure 1.

During this so-called pick-up movement, the tag T and string handle S are manipulated by mechanism 179 in the manner now to be described.

Referring to Figures 1, 9, 10, 33, 49, 50 and 52 to 55, inclusive, just before the pick-up device 178 moves down to engage the bag M, the string handle S is engaged by a finger 179a, as shown in Figure 52. The bag M, as it moves around to the position aligning with the gripping tongs 178a, carries the string S attached thereto so as to engage a second finger 179b, as shown in Figure 53. The bag M, as has been described above, is lifted by the elevator member 183 from a vertical position to a horizontal position, during which time the two fingers are caused to separate as shown in Figure 54. This separation criss-crosses the string S and brings the tag T 35 so as to lie in superimposed position on the bag M. Thereafter the fingers 179a and 179b are caused to be brought together and to free the string S and leave the bag M with the string S shortened in a zig-zag loop with the tag T positioned on the bag M as shown in Figure 55. Suitable means for moving the fingers 179a and 179b are provided which operates as follows.

The finger 179a is carried by a bar 179c which in turn is pivoted at 179d on an L-shaped lever 45 179e. Said lever 179e swings on a pivot 179f carried by a bracket 179g which is bolted to the bracket 177 (see Figure 9). The end of the lever 179e extends in off-set relation below the pivot 179f and carries roller 179h which rides on a 50 conical cam 179i, said cam being mounted to turn with the auxiliary cam shaft 181 (see Figure 10).

The finger 179b is carried by a bar 179k. This bar is pivoted at 179m to the top of the L-shaped lever 179e at a spaced distance from 179d as shown in Figures 33 and 50. The in and out movement of the fingers 179a and 179b to and from the string handle S is controlled through the cam 179j. For moving said fingers to and

60 from each other, there is provided suitable means, as for example, a link 179n which connects with a bell crank 179p which is pivoted at 179q on an off-set portion of the rotatable bracket 179e (see Figure 50). The bell crank 179p through rod 179r is connected to a lever 179s which is pivotally mounted on the shaft 180. This lever carries a roller 179t which rides on a cam 179u, the latter being mounted to turn with the auxiliary cam shaft 181. (See Figure 10.)

70 The bar 179k carries the finger 179b and connects with a link 179v which is actuated by a bell crank 179w, the latter being fulcrumed at 179x on the off-set portion of the bracket 179e at a spaced distance below the pivot 179q. Said bell crank 179w through a connecting rod 179y con-

ncts with a lever 179₂ which carries a roller 179₁ riding on a cam 179₀, the latter being mounted on the auxiliary cam shaft 181.

In order to eliminate any lost motion of the roller on the cams, as shown in Figure 10, each of the connecting rods 182_f, 178_h, 178_v, 179_x and 179_r is provided with a spring 185 which is anchored to the bracket 177 and tends to resiliently press the rollers 183_h, 178_k, 178_x, 179_i and 179_t against their respective cooperating cams. The roller 179_h, however, is held resiliently against the conical cam 179₀ by a horizontally disposed spring 186 which has one end fastened to the link 179_e and the other end anchored to the frame H as shown in Figure 1.

The fingers 179_a and 179_b extend a considerable distance beyond their pivoted supports 179_d and 179_u, and to eliminate any tendency for them to vibrate or otherwise move undesirably, there is provided a guiding brace 187 which is mounted at 187_a to extend from the off-set portion of the bracket 178_e. The brace 187 consists of bifurcated portions 187_b and 187_c which are positioned so that the finger 179_a rides over the outer side of the bifurcation 187_b and the finger 179_b rides between portions 187_b and 187_c. (See Figures 33 and 53.)

The movements of the fingers 179_a and 179_b are controlled by the actions of the cam operated rods above described and said fingers move from an extended position shown in dotted lines in Figure 33 and in Figure 52 where they first engage the string handle S, to a retracted position shown in full lines in Figures 33 and 54 with said fingers separated and thereafter to a position for releasing the string handle S, as shown in Figure 55.

After the bag M has been raised to the horizontal plane and fingers 179_a and 179_b criss-cross the string handle S and disengage themselves therefrom, the tag T is in the superimposed position shown in Figure 55. The entire pick-up mechanism 178 then swings from the position shown in Figure 33 to a position so that the bag M lies in a plane over the discharge conveyor 188. The pick-up device 178 then is released through the action of the cams and interconnected parts as described above, the bag M placed onto the conveyor belt 188 of said apparatus F and transported by said belt 188 to the end thereof adjacent discharge pulley 188_b. From the conveyor belt 188 the bags M may be taken by an operator and packed for shipment.

The drive pulley 188_a of the conveyor is turned by a sprocket 188_c and sprocket chain drive 188_d which includes a small sprocket 188_e mounted to turn with the auxiliary cam shaft 181 (see Figures 1 and 10). The structure of said conveyor 188 and the pulleys 188_b and 188_c is supported by suitable means, such as a pair of spaced brackets 188_f and 188_g bolted to the frame H. If desired, a suitable belt tightener 188_h may be provided adjacent the delivering pulley 188_b.

If for any reason the pick-up device 178 fails to engage the bags M and are carried by the "sixth station," the walls of each carrier receptacle 129 which now open to release the bag M passes an ejecting pin 189 which is interposed in the path of movement of said carrier 129 for dislodging the bags therefrom. Said pin 189 is carried by a plate 189_a supported by a bracket 189_b bolted to the top of the frame H as shown in Figures 1 and 25.

String handle and tag supplying and feeding mechanism

The string handle S and tag T units are fed from a spool arrangement carrying about one thousand units in a continuous strand, similar to the type fully described in Patent No. 1,955,809, granted to Louis Hirschhorn et al., on April 24, 1934, but whereas the feeding of the string handle S and tag T units are intermittently fed in the construction disclosed in said patent, in the present construction, such feeding is carried on by a continuous motion in the manner now to be described.

The mechanism U for supplying and feeding these string handles S and tags T to the stapling machine E, as seen from Figures 5, 9 and 10, is driven through a vertical shaft 190 carrying on its upper end the bevelled gear 182_b which meshes with the gear 182_c, the latter being driven from the cam shaft 84_a. The gear 182_a which also meshes with gear 182_b drives the auxiliary cam shaft 182_a (see Figure 10). The shaft 190 is journaled at the top in a bracket bearing 190_a which may be formed as part of the bracket 177, and at the bottom in a bearing block 190_b bolted to the frame H (see Figures 5 and 9). On the lower end of the shaft 190 a sprocket 190_c is secured to turn therewith, and a chain 190_d drives said sprocket 190_c from a sprocket 190_e which is mounted to turn a shaft 190_f. The latter is mounted on a base 190_g and turns the spool 191 on which the string handle S and tag T units are wound in a continuous spiral length. Said shaft 190_f also drives a pair of mesh gears 190_h which turns a feed screw 190_j for raising the spool 191 to correspond to the unwinding of the string handles S and tags T starting from the top of the spool, the spool 191 being turned in a clockwise rotation.

Also mounted on the shaft 190 above the sprocket 190_c is a cylindrical cam 190_k which has a cam slot 190_m in which rides a roller 190_n, the latter being carried by the end of a lever 190_p which is pivotally mounted to turn with a shaft 190_q. The shaft 190_q is supported by a bracket 190_r from the frame H (see Figure 11). Also secured to turn with the shaft 190_q is another lever 190_s which through a link 190_t actuates a first string handle-tag carrier 196. A second roller 190_v which is carried on an arm 190_w also rides in the cam slot 190_m. Said arm 190_w forms part of a bell crank 190_x, the latter being loosely mounted to turn on the shaft 190_q. The bell crank 190_x has a link 190_y which actuates a second string handle-tag carrier 195. The string handle-tag carriers 196 and 195 operate alternately and are mounted to pivot on a shaft 81 which may be secured to frame H adjacent block 190_b (see Figures 5 and 9). By the provision of said alternately operating carriers, the mechanism U for supplying and feeding the string handles S and tags T operates continuously instead of intermittently.

The feeding of the string handle S and tag T from the spool 191 to the stapling mechanism E takes place as follows. There is provided a tag straightening guiding means 192 comprising a top plate 192_a and a deflector plate 192_b spaced therefrom in a superimposed position, said plates being secured to the frame 66_a as shown in Figures 33 and 45. The string handles S with the tags T pass between the two plates and the tags T are guided to extend

along the string handles S in a position in a horizontal plane.

The plate 192b on opposite sides of the path of movement of the string handle S is provided with spaced protuberances 192c between which the string handle S is guided. Said protuberances may also serve to align the tags T to lie against the string handles S as they pass there-over.

After the string handle S carrying the tag T passes the protuberances 192c of the plate 192b, it is engaged by a finger 193. Said finger terminates an arm 193a which is fulcrumed at 193b on one end 193d of a lever 193c. Said end 193d serves as a stop for limiting the downswing movement of the arm 193a. The other end 193e of said lever 193c is pivoted at 193f on a bracket 193g extending from the frame 66a. The lever 193c is actuated through a rod 193h pivoted at 193j to a projecting end 193k of a lever 193m as shown in Figures 6 and 45, the lever 193m being pivotally mounted at 193n to the shaft 184d. The lever 193m also carries along a mid-portion thereof a roller 193p which rides on a cam 193q, the latter being mounted to turn with the cam shaft 84a. See Figure 6.

In order to normally keep the arm 193a against the stop 193d, there is provided a tension spring 193r as shown in Figure 45. As the cam 193q actuates the above described interconnection linkage for moving the arm 193a with the finger 193, it carries the tag T of the string handle S forward so that the latter passes between the fixed jaw 194a and the movable jaw 194b of a gripper 194 which is carried by the yoke supporting means 194c. The fixed jaw 194a preferably forms an integral part of an extension portion 194d which may in turn be integrally formed with the yoke supporting means 194c. The movable jaw 194b is pivoted at 194e on the extension portion 194d. Since the movable jaw 194a swings in the plane of the extension portion 194d, it requires a second pivoting point because of the U-shape of the yoke supporting means 194c. To this end, the movable jaw 194b has a U-shaped extension 194f conforming to said means 194c which is pivoted at 194g on the lower end 194h of said yoke means 194c. For actuating said extension 194f to swing the jaw 194b, there is provided a reciprocable bolt or pin 194j which has a bevelled upper end 194k. Said end is adapted to engage the projecting portion 194m of the extension 194f. The bolt or pin 194j passes through a sleeve portion 195a of the string tag carrier 195. The pin 194j is retained in a retracted position by a compressing spring 197 which is interposed between the sleeve 195a and a clamp end 194n of a rod 194p. The latter rides in a half round groove support 195b of the carrier 195, as seen in Figures 9 and 11.

The lower end 194r of the rod 194p is movably supported in a bearing 195c of a projecting portion 195d of the unit 195 and is actuated by an L-shaped lever arm 194s which has one end 194t thereof pivoted to the frame H at 194u. The upper end 194v of the lever arm 194s carries a roller 194w which rides on a cam 194x, said cam being mounted to turn with the cam shaft 84a. As shown in Figures 9, 10 and 11, on actuation of lever 194s, a projection 194y which terminates the end 194t through the rod 194p, raises the pin 194j for moving the extension 194f which in turn, as described above, swings the movable jaw 194b into effective position, the spring 197 serving to

retract the pin 194j for normally retaining the movable jaw 194b in a non-gripping condition.

As the gripper 194 approaches the stapling device E, with a tag T carried behind the gripper 194, there is provided a hook 198 which engages the string handle S following the tag T for taking up all the slack or retaining the string handle S in tension so that when the string handle S portion following the tag T reaches the stapling position, the string handle portion is held taut and in proper location for stapling. The hook 198 is pivotally mounted at 198a of a bell crank 198b, which in turn is pivoted at 198c on a pin 198d. The latter rides in a cam slot 198e formed in a bracket 198f bolted to a horizontally extending plate of the bedframe H as shown in Figure 9.

In order to guide the bell crank 198b in the movement of the pin 198d in the slot 198e, a tail rod 198g is provided which slides in the block 198h mounted on the bracket 198f. A lower end 198j of the bell crank 198b is pivotally connected at 198k with an L-shaped lever 198m. The L-shaped lever 198m carries a roller 198p which rides on a cam 198q mounted to turn with the cam shaft 84a. The roller 198p is retained in position for riding against the cam 198q by a tension spring 198r which has one end anchored on the bed frame H and the other end is anchored at 198s on lever 198m. The hook 198 may be retained in a downward swung position by any suitable means such as a tension spring 198t. See Figures 6 and 9.

When the hook 198 is in its lowest position, and the string handle S has been drawn to subject it to a tension, the cutter 176 severs the portion of said string handle S following the tag T in the manner heretofore described, the staple P being applied at approximately the time the cutting of the string handle S strand takes place. This permits the tag T to dangle from the bag M which is carried on the receptacle carrier arm 130 just before being picked up by device 178 as shown in Figures 45 and 46. The tag T before the end of the string handle is stapled is held by a gripper 199 which is similar in all respects to the gripper 194 described above, with the exception as will hereinafter be pointed out. The gripper 194 then is coacting with the tag straightening guide means 192 and the finger 193. After the string handle S thread has been cut, the tag T is released from the gripper 199 and the latter is moved back towards the tag straightening guide means 192 while simultaneously gripper 194 moves forward with a string handle S and a tag T retained as above described for gripper 199, to the stapling mechanism E.

The gripper 199 is provided with a fixed jaw 199a and movable jaw 199b. However, instead of having a yoke supporting means such as 194c of gripper 194, it has an L-shaped upright 199c. The gripper 199 construction requires but a single pivot 199e which swingably secures to the L-shaped upright 199c, an L-shaped arm 199f. A reciprocable pin 199g which is bevelled at its upper end at 199h engages with a portion 199m of the L-shaped arm 199f in a sleeve portion 196a of the tag carrier 196. A compression spring 197 is interposed between 196a and the clamp end 200n of a rod 200p, the lower end of the rod 200p which rides on a half round groove support 196b of the unit 196.

As seen in Figure 11, an L-shaped lever arm 200s has a lower end 200t pivoted at 194u, and an upper end 200v thereof provided with a roller 200w which rides on a cam 200x mounted to turn

with the cam shaft 84a. A projection 200y terminating said end 200r which through rod 200p raises the pin 199j for swinging the movable jaw 199b, the spring 197 serving to retract the pin 199j for normally retaining the movable jaw 199b in a non gripping position.

The operation of the rod 199j is as follows: as the upper end 199h of said rod 199j is moved up, it engages the lever arm 199f and swings the same against the action of a flat spring 201 which is secured to the upright 199c. This movement of arm 199f rocks the jaw 199b which through a socket joint connection 202 is effective to coact with the fixed jaw 199a.

The gripper 194 moves the string handle S and tag T towards the stapling device E while the gripper 199 moves back to engage the string handle S and tag T in the identical manner shown in Figure 45 for the finger 193 and the tag straightening guide means 192 cooperating with the gripper 194. The cam 190k through the interconnecting linkage and bell crank reciprocates the carriers 195 and 196 while the two cams 194x and 200x actuate the grippers 194 and 199, respectively. In order to guide the carriers 195 and 196 in their consecutive movements, a switch plate 203 projecting from the frame H is provided having slots 203a and 203b. Said slots 203a and 203b have washers 203c and rollers 203d which are fitted to the sleeves 195a and 196a of the units 195 and 196, respectively. (See Figures 9, 45 and 46.)

Machine control means

Now referring to Figures 1, 3, 4, 6, 7 and 8, the control lever 65, through which the machine 60 is connected to a suitable power source such as a motor drive (not shown), has a belt 65a which runs on a pulley 65b, the latter being mounted for free rotation on the power shaft 74. A suitable clutch 65d is provided to releasably secure said pulley 65b to the shaft 74, said clutch 65d being operated through one arm 65c of a bell crank 65e pivoted at 65f of the frame H. The other arm 65g of said bell crank 65e connects through a rod 65h with a lever 65j which is secured thereto, by any suitable means as for example a set screw 65k, said lever 65j being pivoted at 65m on a plate 65n which is pivotally mounted at 65p to the frame H. The pivots 65m and 65p are arranged for right angle movements in respect to each other to permit the swinging of the control lever 65 in two different planes in the manner hereinafter described. The control lever 65 is manipulated through the operation of the knob 65q which may be depressed for projecting a pin 65r connected therewith to release the latch 65s held in locked engagement by a compression spring 65t, said latch being pivoted at 65u.

To start the machine, the knob 65q of the control is depressed to release the latch 65s and is swung to the position shown in dotted lines in Figure 8. This through the connecting rods and linkage rocks the bell crank 65e and throws the clutch 65d to effective position for engaging the pulley 65b with the power shaft 65c. In this engaged position, said shaft 74 is caused to rotate the pulley 65b and turn the pinion of the helical gears 73. The latter turn the shaft 75 which drives all the moving parts of the apparatus, devices and mechanisms of the machines 60 as well as the sewing machines 109 and 153 through the pulleys 109a and 162a which turn with the shaft 74.

It is often desirable to run only part of the machine 60 and to leave part of said machine inoperative, as for example to operate the machine 60 with the stapling device E and the string handle S and tag T supply shut off. To this end the control lever 65 may be manipulated through the knob 65q by swinging the plate 65n on the pivot 65p, shown in dotted lines in Figure 7. The plate 65n has a projecting cam 65v which cooperates with a roller 65w mounted to terminate clutch lever 65x. The latter is pivoted at 65y from the frame H which has the end 65z thereof opposite the roller 65w adapted to engage a dog 204. Said dog is pivoted at 204a on a lever 204b which is secured through hub 204c to rotate with the shaft 84a. The latter aligns with the cam shaft 84 and forms a continuation thereof but is free to turn with respect thereto, as shown in Figure 5. The dog 204 is terminated at one end by a latch tooth 204d and at the other end by a tail portion 204e which cooperates with lever end 65z. The latch tooth 204d is adapted to engage with a notch 84b in a disc 84c which is secured to turn with the cam shaft 84.

In order that the latch 204d of the dog 204 may be forced to engage in the notch 84b, a tension spring 204h is provided which has one end anchored at 204f on said hub 204c and the other end anchored at 204g on the latch tooth 204d. Normally the latch tooth 204a of the dog 204 engages in the notch 84b, as shown in Figure 3, thereby causing the shaft 84a to rotate with the shaft 84 at which time all the parts of the machine 60 operate automatically in timed relation. When, however, the knob 65q is swung into the position shown in dotted lines in Figure 7, the end 65z of the clutch lever 65x engages the dog tail portion 204e and swings the latch tooth 204d out of engagement with the notch 84b against the action of a spring 204h. The driving connection between the shaft 84 and 84a is broken making inoperative all the driving mechanism in connection with said device E including the string handle S and tag T supply driven by the shaft 84a while the remaining drives from the shaft 84 continue to operate.

For driving the cam shaft 84 there is provided a sprocket wheel 205 which is secured to turn therewith and through a chain drive 206 is turned by the drive sprocket 207, the latter being secured to turn with the countershaft 72. It is through this chain drive that it is made possible to have all the cams secured to turn with the cam shaft 84 in timed relation with the various other drives connected with or cooperating with the jack shaft 72.

The operation of the machine

The full automatic operation of the machine 60 will now be readily understood from the various drawings and the description of the interconnected apparatus, mechanisms and devices given above.

The machine 60 is first provided with a supply of bagging material in the form of a roll of tubular strip M3 in the cloth supply C and the leading end of said tubular cloth strip is drawn up into the feeding position in mechanism 83, with the tongue member 85 inserted in the upper end of the tubular strip M3, the upper edge of said strip and tongue member being brought to the level just short of the shear blades 86. A supply of tea is put in receptacle 61. A fully wound string and tag spool 191 is mounted to turn on the shaft 190f, said spool 191 being then set in

its lowest position, and the stapler of device E is provided with a supply of wire W extending in through the conduit 173. (See Figures 1, 9 and 38.)

After the source of power, such as a motor (not shown) is started up and made available, the machine control lever 65 is operated through the knob 65g by swinging same from the full line position shown in Figure 8 to the dotted line position for connecting in the driving and power transmission G. This operates the clutch 65d which through said transmission G drives the bag making apparatus B.

The apparatus B at the "first station" through mechanism 83, automatically feeds the bagging material strip M3, cuts the same by means of the shears 86 into sections M2 and in timed relation applies such sections to the fingers 90 of the apparatus B.

At the "second station" the overlocked stitched bottom closure seams Q are applied to the bag sections M2 by means of the sewing machine 109 which is mounted to oscillate with an intermittent movement. The strand R which interconnects the seams between adjacent bags M1 is severed by the shears 116, and since the bags M1 are mounted close together, there is no waste or extra work required in trimming.

The bags M1 at the "third station" are filled with a predetermined quantity of tea by the supply feed measuring mechanism A.

The filled bags M1 at the "fourth station" are transferred from the apparatus B to the top closure apparatus D. This latter apparatus carries the bags M1 through the stationary sewing machine 153 where the overlocked stitched top closure seams O are applied. The strand R which interconnects the seams between adjacent bags M4 is severed by the shears 70, and since the bags are brought close together by the operation of the apparatus D, there is no waste or extra work required in trimming.

The bags M4 then pass to the "fifth station" where a string handle S and tag T unit is riveted to the mid-portion of each bag M4 at the top closure just under the seam O by the stapling device E. This operation completes the tea-balls M. The bags M are now picked up by the transferring and tag positioning mechanism N and while being moved from the device E to the discharge apparatus F, the string handle S is arranged in criss-cross fashion and the tag T is superimposed upon the bag so as to be non-tangling, the completed tea-ball M being delivered to the discharge belt conveyor 188, ready to pack for shipment.

It will thus be seen that there is provided a machine in which the several objects of this invention are achieved and which are well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In a machine having a bag closure means to retain an essence containing product of the character described, a stapling device, and multiple means for supplying a string handle and tag to said stapling device alternately at the bag closure formed by said first mentioned means, and means

for actuating said stapling device and multiple means in timed relation to complete a continuous manufacturing operation.

2. In a machine having mechanisms to form sewn seam flat-sided bags and to fill said bags with an essence containing product and to close the bags for retaining said products therein, means for applying string handles terminated by tags for completely finishing said closed bags, means for folding said string handles with the tags positioned against the flat sides of the bags, and means for discharging from the machine said finished bags after said string holding means are effective.

3. In a machine construction of the character described, a bag material supply means positioned at one level, means for cutting said material into sections positioned above said supply means, a carrier having holding means of the depending type for receiving said sections of the bag material above said cutting means, means for sewing bottom closure seams and filling the bags formed of said sections with an essence containing product while the bag sections are supported on said carrier holding means.

4. In a machine of the character described, a carrier for receiving sections of tubular bag material, and a tongue means extending wholly within the tubular bag material and movable therewith in one direction and movable with respect thereto in the opposite direction.

5. In a machine of the character described, bag forming supply means for feeding preformed tubular material, a carrier for receiving sections of said bag material, a tongue portion positioned wholly within the tubular bag material so constructed and arranged to cooperate with portions of said supply means located wholly outside said tubular material.

6. In a machine of the character described for making tea balls with string handles terminated by tags, means for folding each string handle against the bag and thereafter discharging the same from the machine with said string handle folded.

7. In a machine defined in claim 6 a mechanism for transferring each of said bags from a string and tag attaching means to a discharge means, said transfer means being operated simultaneously with the folding of the string handles.

8. In a bagging machine for forming and filling and closing an essence containing product in flat-sided bags, means for attaching to each filled and closed bag a string handle terminated by a tag, and automatic means operated in timed relation with the first mentioned means for folding the string handles against the flat side of the completely assembled bags ready for packing in non-tangling form.

9. In a machine of the character described, means for discharging in one plane completely assembled tea balls with string handles and tags positioned against the balls, and a mechanism for swinging said balls from another plane to fold and position the string handles and tags against the balls prior to being discharged.

10. In a machine of the character described the combination of a closure means for retaining essence containing product in bags, a stapling device spaced from said bag closure means, means for moving successive bags from closely spaced positions at said closure means to widely spaced positions at the stapling device, a string handle and tag supply means, means for feeding string handles and tags from said supply means to the

stapling device, and means for actuating said bag closure means, stapling device and bag moving, string handle and tag feeding means in timed relation to complete a continuous manufacturing operation.

11. In a machine for making closed filled bags of the character described, a stapling mechanism, and a plurality of reciprocating devices for feeding string handles terminated by tags to said stapling mechanism one at a time for attaching one end of each string handle to a closed bag.

12. In a machine of the character described a "first station" means to mount bag material sections on a carrier having holding means of the depending type, a "second station" means for ap-

plying bottom closures to said bag sections while said bag sections are intermittently in motion with said carrier, a "third station" means for filling the bags while on the bag section carrier, and a "fourth station" means for transferring the filled bags to a carrier of a top closure apparatus.

13. In a machine of the character described a plurality of spaced elements to advance successive filled bags from a making and filling means to a closing means, and means for moving said elements successively from positions of relatively wide spaced distances apart to positions relatively close together.

MERVIN ALLATT.
